UNITED STATES PATENT OFFICE.

HENNING ANDERSEN, OF MINNEAPOLIS, MINNESOTA.

FASTENING MEANS FOR HINGED DOORS.

Application filed July 11, 1921. Serial No. 483,860.

To all whom it may concern:

Be it known that I, HENNING ANDERSEN, a subject of the Kingdom of Denmark, resident of Minneapolis, county of Hennepin, and State of Minnesota, have invented certain new and useful Improvements in Fastening Means for Hinged Doors, of which the following is a specification.

This invention relates to new and useful improvements in a fastening means for hinged doors. This invention is particularly adapted to effect the secure closure of doors which are warped or do not swing true on their hinges. For example, take the case of a door which has downwardly sagged on its hinges with the result that the upper marginal portions of the door are spaced from its frame when in closed position. When this novel rod and complementary member are placed upon the adjacent vertical marginal portions of the door and door frame, closure of the door causes these co-operable parts to force the door rearwardly against its sagged hinge so that the door is forced into proper alignment with the frame. The action of the complementary parts of this invention is in the nature of a toggle joint, so that when the door is closed, it is held against accidental opening.

While the term "doors" is employed, it is to be understood that this invention is equally applicable to windows of the hinged type, such for example, as French windows.

The object of this invention therefore is to provide an improved fastening means for hinged doors.

Other objects of the invention will more fully appear from the following description and the accompanying drawings and will be pointed out in the annexed claims.

In the drawings, there has been disclosed a structure designed to carry out the objects of the invention, but it is to be understood that the invention is not confined to the exact features shown, as various changes may be made within the scope of the claims which follow.

In the drawings:

Figure 1 is a view in cross section of a hinged door and its complementary frame and showing the invention applied thereto;

Figure 2 is a cross section on the line 2-2 of Figure 3, and showing the parts in enlarged detail;

Figure 3 is a vertical section on the line 3-3 of Figure 2.

In this selected embodiment of the invention there is shown a door 4 mounted on the door frame 5 by means of a hinge 6. The door 4 is shown as adapted to be swung to close the door-way between the frames 5 and 7. The invention broadly provides a pivoted lever or rod carried by a marginal portion of the door and adapted to engage a member secured to the complementary door frame. The pivoted rod and door frame member may both be positioned on the vertical marginal portions of the door and frame or on the horizontal marginal portions of the door and frame. They are preferably positioned where they will be most effective in righting the particular sag or warping of a door and thereby hold the door in securely closed position. As shown in the drawings the co-operable parts are positioned upon the vertical or upright marginal portions of the door frame 7 and the door 4.

A recess 8 is preferably provided in the marginal portion of the door and metallic plates 9 and 11 are secured by screws to the adjacent portions of the door 4 so that the plates are positioned along the opposed horizontal sides of the recess. A pivot pin 12 is carried by the lower plate 11 and extends vertically substantially across the recess 8. The rod 13 is preferably formed with an integral enlarged portion 14 which is apertured and thereby mounted upon the pivot pin 12 for swinging movement thereon. The recess side 15 is inclined outwardly with relation to the vertical plane of the door passing through the pivot pin 12, so that, as shown in dotted and full line positions in Figure 1, the rod may swing through the vertical plane of the door passing through the pivot pin.

Means are provided yieldably to hold the rod to one side of such vertical plane of the door. As here shown, such yieldable means consists of a torsion spring 16 coiled about the pivot pin 12 and having one spring end anchored to the pin by insertion in a recess formed in the pin. The other end portion 17 of the spring extends from the pin and is terminally offset to engage the rod 13 normally to hold the rod in the position shown in the dotted lines in Figure 1. The rod is adapted to project from the door recess to engage a complementary

member secured to an adjacent portion of the door frame. The effective length of the rod is preferably adjustable as by means of an interiorly threaded head 18 received 5 in adjustable threaded engagement on the end of the rod.

The co-operable door frame member is provided by the metallic catch 19 screwed in a recess in the door frame 7. This catch 10 is provided with an outwardly presented recess 21 which is adapted to receive the head 18 as the door is arcuately swung to closed position.

The terminal face 22 of the head 18 is 15 preferably inclined slightly toward the inclined side 15 of the door recess.

As the door is swung closed from its dotted line position shown in Figure 1, the rod 13 is yieldably held against the inclined side 15 of the recess. In such position, the rod does not attain its maximum projection from the door recess. Closure of the door causes the end of the head to pass within the recessed catch member, 25 wherein the head is held during completion of door closing so that relative movement of the door and rod is had, and the rod is swung through the vertical plane of the door passing through the pivot pin 12. The result of such relative rod movement 30 is to increase the effective extension of the rod head from the door recess so that the adjacent door portion is thrust in the direction of the door hinges and the door is thereby trued to its frame and thus held in 35 closed position. Furthermore, the door is secured in such fully closed position against accidental opening as an opening force must be exerted upon the door sufficient 40 to cause the rod to again pass through the vertical plane of the door containing the pivot pin 12.

I claim as my invention:

1. Fastening means for hinged doors including, a rod, a pivotal mounting for the rod adjacent the marginal portion of the door, and a member secured to a complementary door frame and adapted to be engaged by the rod as the door is closed, the 45 rod being of a length that when in contact with the door-frame member a longitudinal thrust is exerted through the rod in movement from one side to the other of a line passing through the pivot of the rod.

2. Fastening means for hinged doors including, a rod, a pivotal mounting for the rod in a recess in the marginal portion of the door, and a catch secured in a recess in a complementary door frame, the rod projecting from the door recess and being adapted to engage the catch as the door is closed, the rod being of a length that when 60 in contact with the door-frame catch a longitudinal thrust is exerted through the

rod in movement from one side to the other 65 of a line passing through the pivot of the rod.

3. Fastening means for hinged doors including, a rod, a pivotal mounting for the rod adjacent a marginal portion of the door, 70 means yieldably to hold the rod to one side of the vertical plane of the door through said mounting, a catch secured to a complementary door frame and adapted to be engaged by the rod as the door is closed, 75 the rod being of a length that when in contact with the door-frame catch a longitudinal thrust is exerted through the rod as it yieldably swings from one side to the other of a line passing through the pivot 80 of the rod.

4. Fastening means for hinged doors including, a rod, a pivotal mounting for the rod adjacent the marginal portion of the door whereby the rod may swing in a horizontal plane, means yieldably to hold the rod to one side of the vertical plane of the door passing through said mounting, and a catch secured to a complementary door frame and adapted to be engaged by the rod 90 as the door is closed, whereby upon closure of the door, a longitudinal thrust is exerted through the rod and the rod is caused to swing horizontally through said vertical plane and accidental opening of the door is 95 thereafter prevented.

5. Fastening means for hinged doors including, a rod, a pivotal mounting for the rod adjacent the marginal portion of the door, a head adjustably mounted on the end 100 of the rod, and a catch secured to a complementary door frame and adapted to be engaged by said head as the door is closed, the head being adjusted so as to force the adjacent door portion away from the adjacent frame portion whereby the door may 105 be held in securely closed position.

6. Fastening means for hinged doors including, a rod, a pivotal mounting for the rod adjacent the marginal portion of the door, a spring carried by the door and engaging the rod yieldably to hold the rod to one side of the vertical plane of the door passing through said mounting, and a catch secured to a complementary door frame and 110 adapted to be engaged by the rod as the door is closed, whereby upon closure of the door, a longitudinal thrust is exerted through the rod and the rod is caused yieldably to swing through the vertical plane 115 and accidental opening of the door is thereafter prevented.

7. Fastening means for hinged doors including a plate secured in a recess adjacent the marginal portion of the door, a pivot pin carried by the plate, a rod mounted on the pivot pin and projecting from said recess, means yieldably to hold the rod 125

to one side of the vertical plane of the door passing through said pivot pin, and a catch secured to a complementary door frame and adapted to be engaged by the rod as the door is closed, whereby upon closure of the door, a longitudinal thrust is exerted through the rod and the rod is caused

yieldably to swing through said vertical plane and accidental opening of the door is thereafter prevented.

10

In witness whereof, I have hereunto set my hand this 7th day of July, 1921.

HENNING ANDERSEN.
